UNITED STATES PATENT OFFICE.

ARMAND S. MADDEN, OF CHICAGO, ILLINOIS.

GARMENT-SUPPORTING DEVICE.

1,124,771.

Specification of Letters Patent. Patented Jan. 12, 1915.

Application filed February 18, 1914. Serial No. 819,377.

To all whom it may concern:

Be it known that I, ARMAND S. MADDEN, a citizen of the United States, residing at Chicago, in the county of Cook and State 5 of Illinois, have invented a new and useful Improvement in Garment-Supporting Devices, of which the following is a specification.

My invention relates to certain new and 10 useful improvements in garment-supporting devices, and is fully described and explained in the specification and shown in the accompanying drawings, in which:

Figure 1 is a front view of my improved 15 device, a part of the bag being broken away to show the interior; Fig. 2 is a section on the line 2 of Fig. 1, and Fig. 3 is a section on the line 3 of Fig. 1.

Referring to the drawings, 4 is a tight 20 bag to which access may be had through an opening closed by snaps 5. The bag is supported by a frame constructed in the following manner: A frame is made of one piece of wire having a central transverse 25 part or strut 6. The wire at the two ends of this strut is turned in opposite directions to form the parts 7, each of which recurses at 8 and returns, as shown at 9, to the opposite end of the strut from that at which it 30 started, the ends of the parts 9 being bent around the strut, as shown at 10. There is thus provided in the simplest possible way a light, but fairly strong, frame which can lie in the upper part of the bag 4 to hold 35 the same in position. The medial strut with which this frame is provided serves two purposes. The ends of the strut afford means of attachment for the furcations 11 of a bifurcated hook 12 which passes out 40 through a small opening in the bag 4, this opening being of such size as to tightly fit the wires of the hook to prevent the entrance of dust. The entire structure can, therefore, readily be hung up in a closet and will 45 occupy but a small space. The strut 6 also serves as a support for clothes hangers 13, and it is made of such length as to take, in

practice, three such hangers side by side, as shown in Fig. 3. The wire frame which supports and distends the bag 4 is, as illustrated, made considerably longer than the hangers themselves which are adapted to be placed therein, and in turn receive garments whose weight is supported by the strut 6 and which are protected from moths, 50 dust and dirt by the bag 4 carried by the wire-frame.

The hook 12 is pivotally mounted on the strut 6 so that it can be swung down to permit the entire structure to be folded up in 60 a compact bundle for packing.

I realize that considerable variation is possible in the details of the construction herein shown, and I do not intend to limit myself thereto, except as pointed out in 65 the following claim, in which it is my intention to claim all the novelty inherent in the device as broadly as is permitted by the state of the art.

What I claim as new and desire to secure by Letters Patent is:

In combination, a relatively wide and substantially elliptical bag supporting frame having a central transverse strut adapted to support a plurality of coat hangers of less 75 length than the frame, said frame being formed from a single piece of wire bent at the middle to form the strut and having its ends bent back upon themselves and attached to the opposite ends of said strut, a 80 supporting hook pivotally mounted on said strut capable of being folded into substantially the plane of the frame, and a bag adapted to inclose said frame and the hangers provided with a perforation through 85 which said hook may be passed and a buttoned front to permit access to the interior.

In testimony whereof I have hereunto set my hand this 14th day of February, 1914.

ARMAND S. MADDEN.
